(57) **CLAIM**

The ornamental design for a hunting decoy, as shown and described.

DESCRIPTION

FIG. 1 is a front and left side isometric view of a hunting decoy, shown in a deployed configuration;

FIG. 2 is a front elevational view of the hunting decoy of FIG. 1;

FIG. 3 is a rear elevational view of the hunting decoy of FIG. 1;

FIG. 4 is a left side elevational view of the hunting decoy of FIG. 1;

FIG. 5 is a right side elevational view of the hunting decoy of FIG. 1;

FIG. 6 is a top plan view of the hunting decoy of FIG. 1;

FIG. 7 is a bottom plan view of the hunting decoy of FIG. 1;

FIG. 8 is a front, bottom and right side isometric view of the hunting decoy of FIG. 1, shown in a folded configuration;

FIG. 9 is a front elevational view of the hunting decoy of FIG. 8;

FIG. 10 is a rear elevational view of the hunting decoy of FIG. 8;

FIG. 11 is a left side elevational view of the hunting decoy of FIG. 8;

FIG. 12 is a right side elevational view of the hunting decoy of FIG. 8;

FIG. 13 is a top plan view of the hunting decoy of FIG. 8; and,

FIG. 14 is a bottom plan view of the hunting decoy of FIG. 8.

The broken lines are included for the purpose of illustrating portions that form no part of the claimed design.
